UNITED STATES PATENT OFFICE.

MILTON H. SHOENBERG, OF SAN FRANCISCO, CALIFORNIA, ASSIGNOR, BY DIRECT AND MESNE ASSIGNMENTS, TO CONSOLIDATED ELECTRIC APPLIANCE COMPANIES, LTD., OF SAN FRANCISCO, CALIFORNIA, A CORPORATION OF CALIFORNIA.

ELECTRICAL HEATER AND EXPANSION COIL.

No. 856,736.

Specification of Letters Patent.

Patented June 11, 1907.

Application filed September 13, 1906. Serial No. 334,409.

To all whom it may concern:

Be it known that I, MILTON H. SHOENBERG, a citizen of the United States, residing at the city and county of San Francisco and State of California, have invented new and useful Improvements in Electrical Heater and Expansion Coils, of which the following is a specification.

My invention relates to a heating apparatus.

It consists in the combination of one or more tubes through which heat is transmitted, said tubes having an elastic expandable electrical resistant conducting coil located within the insulated lining, and connections whereby an electrical current may be passed there-through, and in details of construction which will be more fully explained by reference to the accompanying drawings, in which—

Figure 1 is a vertical section. Fig. 2 is a perspective view.

It is the object of this invention to provide a device in which the elasticity of an insulating interior coating and of a conducting coil, may be utilized to maintain a sufficiently close contact between these interior parts and the tube, so that the greater portion of the heat derived from the resistant coil will be transmitted through the tube to heat the medium which may be in contact with the tube.

A is a metal tube of which there may be any desired number arranged parallel with each other and having the ends supported in suitable bearings. Within this tube an insulating sheet 2 is caused to expand. Mica having a certain amount of elasticity may be cut to such a size that it will just fill the interior of the tube when expanded, and being introduced its elasticity will cause it to expand and fit snugly against the interior of the tube.

3 is a coil of naked wire which is a good electrical conductor. This coil is of such diameter that it will fit snugly within the insulating lining 2. It may be introduced by coiling it so as to reduce the diameter of the coils, and after being introduced, it is allowed to expand and will thus press against the mica, holding the latter in close contact with the interior of the metal tube A, thus insur-

ing the best transmission of heat through the substance of the tube.

4 are porcelain or other non-conducting bushings inserted in the ends of the tube A, and within these bushings are fitted the plugs 5 with which the ends of the coil 3 are connected.

By means of suitable plug or connection as at 6 the line wires 7 may be connected so that a current of any desired intensity may be caused to pass through the coil 3. The current being in excess of the capacity of the coil, it will be manifest that the temperature of the coil will be elevated, and the tube 65 or tubes A will be correspondingly heated. In Fig. 1, I have shown tubes of this sort passing through an exterior chamber 8 which may contain water or any heat conductor through which the heat may be utilized. 70

In Fig. 2 I have shown the tubes A arranged within a frame or container 9 so that the conductor to which the heat is to be transmitted may be laid upon the tubes in the form of a metal plate which will serve for 75 cooking purposes.

As shown in this connection, the plugs 6 through which the line wires 7 communicate with the coils interior to the tubes, connect with the opposite ends of the series. Thus, 80 one of the line wires 7 connects through the coil within the first tube A, thence through a transfer plate 10 with a second coil at the opposite end from the plug; thence the current returning through the interior coil is again 85 transferred to the third tube, and its coil, and so on through as many of these coils and tubes as it may be desirable to use in a single series, and from the final tube connection is made to return the current through the line 90 wire 7.

In place of a mica insulation I may employ any suitable insulating substance which can be interposed between the interior of the tube and the coil, the expansion of the coil 95 acting to form a close contact and more perfect transmission of the heat, without reference to the particular insulating medium.

Having thus described my invention, what I claim and desire to secure by Letters Patent is—

1. An electrical heater consisting of an ex-

terior tube, an elastic insulating sheet expanded to fit closely within the tube, an electrical resistant coil expanded to fit the interior of the insulating sheet and retain it in close contact with the tube, and connections whereby an electrical current may be passed through the coil, said connections including non-conducting bushings fixed in the end of the tube, and plugs fixed in the bushings and connecting with the coil.

2. In an electrical heater, a heat conducting tube an insulating sheet fitting within the tube, said sheet consisting of a piece capable of being coiled to initially enter the tube and then expandable to fit snugly against

the interior of said tube, an elastic coil having such diameter as to expand and make close contact between itself, the insulating sheet and the interior of the tube and connections whereby an electrical current may be passed through the coil to heat the latter and the tube, and a medium to be heated with which the exterior of the tube is in contact.

In testimony whereof I have hereunto set my hand in presence of two subscribing witnesses.

MILTON H. SHOENBERG.
